UNITED STATES PATENT OFFICE.

WALTER A. WOOD, OF HOOSICK FALLS, NEW YORK.

IMPROVEMENT IN HARVESTERS.

Specification forming part of Letters Patent No. 71,832, dated December 3, 1867.

To all whom it may concern:

Be it known that I, WALTER A. WOOD, of Hoosick Falls, in the county of Rensselaer and State of New York, have invented certain new and useful Improvements in Grass-Mowing or Harvesting Machines; and I do hereby declare the following to be a full, clear, and exact description of the construction and operation of the same, reference being had to the accompanying drawings, making a part of this specification, in which—

Figure 1 represents a perspective view of the machine. Fig. 2 represents a longitudinal vertical section through the machine. Fig. 3 represents a section through the inner shoe and the finger-bar and spring, or flexible connecting-piece, to show their attachment to each other, and on an enlarged scale.

My invention relates to the manner in which I unite the finger-bar and cutting apparatus to the main frame, which carries the gearing, by means of the inner shoe and flexible or spring connection.

To enable others skilled in the art to make and use my invention, I will proceed to describe the same with reference to the drawings.

A is a main axle, upon which are placed the two driving and supporting wheels B B, said wheels turning independent of the axle, like ordinary carriage-wheels. C is a rectangular main frame, firmly connected to the main axle A, so that it can only turn as the axle turns in its supporting-wheels. The wheels B are furnished with internal gears, D, for giving motion to the sickle, as will be described.

On the rear portion of the main frame, and on the top thereof, is hung, in suitable boxes or bearings, a shaft, E, which carries at each of its ends a drum, F, that has an internal ratchet, a, in it, and a spur-gear wheel, b, on its outside, which gears with the drive-wheel on that side of the machine. The drums F are loose on the axle or shaft E, but are made to turn with it, under certain circumstances, by means of a pawl that takes into the ratchet teeth thereof.

On the shaft E, so as to come within the drums F and be protected by them, there are secured, in a permanent manner, to the shaft E, two blocks, G G, which blocks have pawls c c pivoted to them, that are, by means of springs d d, held into action with the ratchets

a a, the inclination of the ratchets and pawls being such that as the machine moves forward the drums will be held fast to and turn with the shaft E, but when moved backward the ratchets will slip over or past the pawls, the springs d readily yielding for this purpose.

The pawls c c have pins e set in them, and upon the shaft E are hung loose hooks, which will take over said pins and hold the pawls out of gear with the ratchets, and thus the machine may be moved from field to field without running the gearing. On the shaft E there is fastened a bevel-cog wheel, H, that turns a bevel-pinion, I, on a shaft, J, which extends forward and has upon its forward end a crank-wheel, K, which imparts motion, through the pitman Z, to the cutters. The inclination of the front end of the frame downward and the rear end upward brings the crank-wheel K in a desirable position for driving the knife, and elevates the gearing sufficiently to be out of the way of catching the grass, and thus prevents its winding up thereon.

M is a shoe or runner, the rear of which is suspended to the axle A by a stirrup-strap, N, that will allow it some vertical motion or play.

An extension-bar, O, made of flat spring-steel, or some other elastic substance of sufficient strength, is secured to the stubble side of the main frame, and on the under side thereof, near the front outer corner, and on a line or nearly so with the finger-bar, and, curving downward toward the shoe M, fits into a recess, 2, Fig. 3, formed in the shoe. A dowel-pin, 3, formed in the shoe and in the recess, passing through that end of the extension-bar, gives it a firm position in the shoe. The finger-bar P is then laid in its recess, and overlies this end of the extension-bar O, and by passing through the shoe and through the finger-bar the screw g, and running down the nut h, a firm union of the finger-bar, extension-bar, and shoe is made, and thus the cutting apparatus is joined to the main frame, which supports the gearing, laterally by the yielding spring-connection, and longitudinally by the stirrup at the rear of the shoe, passing over the axle; or, if desirable, a stud can be inserted into the edge of the frame to receive it; but I prefer to pass the stirrup over the axle. With this arrangement, the shoe, together with the cutting apparatus, has to a certain degree

the property of yielding up and down independent of the up-and-down movement of the main frame, causing thereby the finger-bar and cutters more readily to conform to the inequalities of the ground, and more effectually to withstand the sudden shocks incident to running against fixed obstacles. At the junction of this spring extension-bar with the shoe a hinge or joint is interposed, as shown at Fig. 3.

That part of the extension-bar which comes in contact with the shoe and underlies the finger-bar projects just far enough to have an eye turned upon it, close to the iron shoe. The other part of the extension-bar is made so as to hinge onto this eye, having ears welded to each side and turned over, and, when astride the eye, a bolt is passed through the two in the ordinary way. This arrangement, in connection with the stirrup-connection of the main shoe to the axle, allows the shoe to turn or roll in the line of its length, and the finger-bar and cutters, to a certain degree, to rise above or fall below a horizontal plane, and independent of the up and down motions of the driving-wheels, and thereby the finger-bar and cutters are caused to follow more closely the unequal surfaces of the ground than they could have done had not the hinge in the extension-bar been interposed.

The washer *i*, between the nut and finger-bar, is of considerable breadth, and affords a back bearing to the sickle-bar, as also a top support, to keep it from rising from the finger-bar. The sickle-bar rests and runs upon the finger-bar, and the flanges on the guards *j* close up the space in front of the sickle-bar, in order to prevent the working of grass or other material under the sickle-bar.

Q is an outside shoe; *R*, a track-cleaner hinged thereto, having a handle, *S*, for the purpose of raising it and for separating more perfectly the cut from the uncut crop. *T* is a seat and tongue-plate, cast in one piece, through which the axle passes, and to which the tongue is bolted, and which is furnished with sockets for the reception of the seat-standards. This seat and tongue-plate turns freely upon the axle, and at its forward end is pivoted the lever *V* for raising and lowering the cutters. This lever is a right-angled lever, or nearly so, with its long arm extending nearly vertical, while its short arm extends forward.

A chain is attached to the end of the short

arm, which extends to the point of the shoe, which allows the driver, by grasping the long arm, to readily raise the shoe and finger-bar, the main frame tilting upon the axle; and when raised, it can be held there by the notches on the standard *X* catching the staple *u* on lever *V*. The short arm *V'* rests upon a support, *s*, fastened to the under side of the pole *U*, and the distance that the shoe can be dropped is determined by the length of the chain which connects the short arm *V'* of the lever with the shoe.

With this mode of construction, it is plain that, the gearing being placed in rear of the axle, the working of the gear tends to crowd down the front end of the frame, as also does the draft, the pole being connected to the axle, and the frame tilting thereon, with the finger-bar in front; consequently the finger-bar and shoe are pressed hard upon the ground. On uneven ground, like ridge and furrow, this pressure tends to elevate the outer end of the finger-bar when the shoe passes into a depression. It is to obviate this difficulty that the hinge is interposed, as heretofore described, which, together with the stirrup at the rear of the shoe, allows sufficient turning to obviate the difficulty, although the finger-bar cannot turn up to a vertical position.

Having thus fully described the nature and object of my improvement, what I claim therein as new, and desire to secure by Letters Patent, is—

1. Connecting the finger-bar and cutting apparatus of a mowing-machine to the main frame thereof by a yielding or spring connection, bolted rigidly at one end to the front outer corner of the main frame, and hinged at the other end directly to the shoe-piece which supports the finger-bar and cutting apparatus.

2. The use, in a mowing-machine, of a shoe-piece or runner, which supports the finger-beam and cutting apparatus, when said shoe-piece is held in place at its rear end by a stirrup or loop passing over an axle, and is held laterally by a yielding spring-connection, hinged at its lower end to the shoe, and bolted at its upper end to the front outer corner of the main frame.
